UNITED STATES PATENT OFFICE.

HENRY J. STUART, OF DERBY, CONNECTICUT, ASSIGNOR TO THE R. N. BASSETT COMPANY, OF DERBY, CONNECTICUT, A CORPORATION OF CONNECTICUT.

TAB-END BUTTON.

1,101,971.

Specification of Letters Patent. Patented June 30, 1914.

Application filed April 11, 1914. Serial No. 831,118.

To all whom it may concern:

Be it known that I, HENRY J. STUART, a citizen of the United States, residing at Derby, New Haven county, State of Connecticut, have invented certain new and useful Improvements in Tab-End Buttons, of which the following is a full, clear, and exact description.

My invention relates to a new and improved method of threading tab end buttons so-called, such devices being commonly employed in connection with hose supporters, the invention in the present case relating merely to the means for connecting the supporting tape to the button element.

In the drawings—Figure 1 is a front view, relatively enlarged. Fig. 2 is a longitudinal section, partially threaded. Fig. 3 is a similar view, fully threaded.

20 1 is a button.

2 is a base plate having three slots therein, one slot being on one side of the button, the other two slots being on the opposite side of the button. These slots are respectively indicated at 3—4—5.

25 6 represents a piece of tape of a width proper to pass through said slots. One end of this tape is secured to the button, while the other end leads up to a suitable support, the upper end of the tape being shown as broken off.

The course of the threading is as follows: The tape passes through the slot 3 from the front to the rear, the slot 3 being the uppermost slot; thence the tape passes down to and around the lower end of the base plate 2; thence upwardly along the front to and through the intermediate slot 4 from the front to the rear; thence down the back to and through the slot 5 from the rear to the front; thence down to and around the lower edge of the base plate 2, and thence up along the back so as to underlie that part of the tape leading from the slot 3 down to 40 and around the lower end. It will be seen that by the tortuous course of the thread-

ing, considerable friction is produced where the bends occur at the lower end of the plate, this friction being sufficient to prevent slippage, thereby doing away with the necessity of any mechanical fastenings or sewing. Again, by this arrangement the danger of cutting the webbing by the lower edge of the plate 2 is reduced to a minimum because at that point where the heaviest strain comes, the inner layer of the web acts as a pad to prevent chafing the outer layer upon which latter length of webbing the strain occurs. It is obvious that the particular order observed in passing the tape through the slots is immaterial, although the simplest and most expeditious method of threading the tape through the frame comprises tucking the two ends of the tape through the slots in the position indicated in Fig. 2, then taking the longer end and turning it back and passing it up and through the slot 3 from the rear to the front, simultaneously turning back the short end so that when the tape is drawn taut, the structure will appear as in Fig. 3.

What I claim is:

In a tab end, a base plate, a button mounted thereon, a single slot in said plate above said button, two slots in said plate below said button, and a tape threaded through said slots as follows: through the upper slot from the front to the rear; thence down to and around the lower edge of the plate; thence up to and through the intermediate slot from the front to the rear; thence down to and through the lowermost slot from the rear to the front; thence down to and around the lower edge of the plate and up along the back thereof, the extreme lower end terminating between the lower edge of the plate and the uppermost slot.

HENRY J. STUART.
